UNITED STATES PATENT OFFICE.

FLORIS HENRICUS BOS, OF HOOGLAND, NETHERLANDS.

KEYHOLE-GUARD.

SPECIFICATION forming part of Letters Patent No. 707,381, dated August 19, 1902.

Application filed February 24, 1902. Serial No. 95,430. (No model.)

To all whom it may concern:

Be it known that I, FLORIS HENRICUS BOS, teacher, a subject of the Queen of the Netherlands, residing at Hoogland, in the Province 5 of Utrecht, in the Kingdom of the Netherlands, have invented certain new and useful Improvements in Keyhole-Guards, of which the following is a specification.

This invention has for its object a secret 10 and thief-proof means for closing the keyholes of safes, strong-rooms, money-boxes, and in general all receptacles, whether made in metal or wood, which are intended to contain valuables.

15 As is well known, of late years the combination principle has been recognized as the most correct means for insuring safety in the construction of the locks of safes and other receptacles for valuables. The essential feature of such locks consists in the provision 20 of a number of constituent elements which are intended to prevent the opening of the lock and to only allow of the same when all said elements are brought into particular 25 places or positions. In the present invention this principle is not applied to the lock itself, but is utilized for rendering it impossible for unauthorized persons to find out the keyhole. The door of a safe provided with this arrangement 30 shows externally a space divided into perfectly equal squares, a knob being arranged on each square, and the keyhole is located behind this space. If attempts are made to turn the handles or knobs, it is 35 found that all the knobs are movable and allow of a little rotation both to right and left. They all turn equally as much and equally stiffly and are confusingly alike. Two or more of these knobs, the position of which is 40 only known to the initiated, are connected with bolts or fasteners. If these bolts are thrown out of engagement by turning the knobs in question, it is then possible to move some slides formed out of a number of the 45 sections and to reach the keyhole.

Some examples of construction are shown in the accompanying drawings, Figure 1 being a front view of the door with the keyhole masked; Fig. 2, a similar view with the key- 50 hole exposed; Fig. 3, a rear view of the door shown in Fig. 1; Fig. 4, an arrangement where three slides are employed; Fig. 5, a cross-sec-

tion, and Fig. 6 an end view, of the door shown in Fig. 1; Fig. 7, a view, on an enlarged scale and in section, of one of the 55 squares, with the parts thereto belonging, from which the closing device is composed; and Fig. 8, a side view or, rather, cross-section of the slides *m* and *n*.

Each of these squares or parts consists of 60 a small steel plate *a*, in which a pin *b*, with a knob *c*, is revolubly arranged. The steel plates *a* are located on the front side of the door-plate *d*, and all four sides of said plates engage by means of tongues and grooves with 65 one another, and the plates thus form when put together in the manner shown in Fig. 1 a regularly-divided field. These steel plates are preferably screwed into the door-plate *d* by means of screws *f* in the manner shown in 70 Fig. 7, the screw-pins *f* being inaccessible from the outside. Each spindle *b* passes through the door-plate *d* and is riveted on the rear side of the same to a rectangular piece of steel *e*.

A plate *g*, with rectangular slots, is arranged on the inner side of the door-plate *d*, in which slots the steel piece *e* fits, Figs. 7 and 3. These slots are so calculated that each of the steel pieces *e* has a slight movement to right and 80 left; but then, in consequence of its rectangular form, it is arrested. In this manner it is possible for all the knobs to describe a uniform rotation to left or right.

The keyhole *o* is situated behind one of the 85 numerous steel plates *a*, and it must not only be kept secret behind which plate it is, but also which plates have to be displaced, and by the turning of which knobs this can be made possible in order to give access to the 90 keyhole. For this object three or more of the squares *a* adjacent to one another are screwed on a common slide, which is let into a recess of the door-plate *d* and the perforated plate *g* and may be moved in the same, together 95 with the three steel plates *a*, Fig. 3. Two such slides *m* *n* are arranged at right angles to one another, of which *m* must be moved upward and then *n* to the left in order to uncover the keyhole *o*. Fig. 2 shows the slides 100 *m* and *n* in shaded lines, while Fig. 8 shows not only the form of the slides, but also that the slot in the door-plate *d* is made somewhat narrower than the recess in the plate *g*. It

is evident that when the slide *m* is pushed upward the highest-placed steel plate *a* must project outside the field, or space within which the squares are placed. In order that at this 5 place no mark should be formed in time, the strip which is left free on the door around the space or field is beveled off, as shown in Fig. 6. Further, the said steel plate is preferably formed as a whole with the next plate, 10 because otherwise a good connection with the slide *m* is not well possible. By turning the knobs *c* the slides *m* *n* may be fixed or released to allow of their movement. This 15 takes place in the following manner: Short lever-arms *v* and *w* are mounted on the prolonged spindles of the knobs *h* and *i*, respectively, Fig. 3, by means of rectangular pieces. These lever-arms engage with bolts *k* and *i*, respectively, which are arranged above on 20 the plate *g*, adjustable in a horizontal direction, and engage in notches in the slide *m*. These bolts are moved forward by turning the knobs *h* and *i*, and according to the direction in which the turning takes place the 25 slide *m* is released or secured. The knobs *h* and *i* are, further, always turned in opposite directions. If the bolts *k* and *l* are released, the slide *m* may be pushed up to a distance equal to the height of one plate *a*, whereupon 30 it is then possible to move the slide *n* to an extent equal to the width of one plate *a*. The keyhole *o* is then exposed. Two reserve-bolts *p* *q*, which are operated by the knobs *r* *s*, but are not used for opening the lock 35 itself, have for their object to render useless all efforts to find out the position of the slides and to release the same by turning all the knobs once to the right and then to the left, as if in this manner the bolts *k* and *l* be turned 40 back by the continued turning of the other knobs the reserve-bolts *p* *q* are brought into action and again lock the slide *m*, and vice versa. As shown in Fig. 3, the reserve-bolt *p* lies on the right-hand side and the reserve-bolt *q* on the left-hand side of the slide *m*. 45 The directions of rotation of the two knobs belonging thereto are thus opposite to one another.

The slides *m* and *n* are secured by guides *u* 50 against being forced in backward. The steel plates or elements *a*, which are screwed on the slides *m* *n*, are all provided with revolvable knobs, their steel pieces *e* being let into recesses on the slide. In the case of the high- 55 est-placed plate *t* of the slide *m*—that is to say, the one which when the slide is pushed upward projects beyond the field—this steel piece *e*, as shown in dotted lines in Fig. 7, is let into the steel plate *t* itself. The slide 60 *n* can only be moved after the slide *m* has been pushed upward, and this slide may also be locked by means of similar bolts, which are moved by other knobs. Of course any desired position may be selected for the lock, 65 and the number of the slides and of the bolts and the position of the knobs moving these bolts may be made to form a large number of

combinations. Thus, for instance, in Fig. 4 a device is shown having three slides, and in this arrangement the vertical slide, consisting of four elements, is first moved outward and then the horizontal slide, composed of two elements, to the right, and, finally, another vertical slide, consisting of two elements, moved downward in order to free the 75 key-hole.

The arrows shown in Figs. 2 and 4 indicate the directions of movement of the slides necessary for closing the keyhole.

In carrying out the invention particular care must be observed that the knobs connected with the bolts are neither more nor less movable and are not movable with more or less difficulty than the other knobs and that the rotation of these knobs is not checked 85 or stopped differently in order that a thief may not be brought onto the right track by feeling or hearing. The knobs must also be so difficult to turn that they do not alter their position by their own weight. The star 90 form is the best for the knobs, while glass or porcelain is found to be the best material for them, because the fingers in opening and closing the safe leave no traces thereon. If the proprietor of the safe has reason to fear 95 that some one has become acquainted with the handling of the safety device, he may adopt a new combination in a simple manner by shortening or lengthening the lever-arms by which the bolts are operated and 100 bringing them into communication with other knobs. The knobs previously employed then again have steel pieces mounted thereon.

I declare that what I claim is—

1. A keyhole closing or obscuring device, 105 comprising a base or mounting plate, a plurality of connected movable plates arranged over said base-plate, and a plurality of slide-pieces carrying upon their outer surfaces certain of said first-mentioned plates, and means 110 for guiding said slide-pieces; substantially as described.

2. A keyhole closing or obscuring device, comprising a mounting-plate, a plurality of small square plates arranged in a regularly- 115 divided field over said plate, means of engagement between said small plates adapted to permit them to move laterally relatively to each other, a plurality of slide-pieces arranged in such manner that one of them cannot be 120 moved until the next has been moved, a plurality of said small square plates arranged on the outer surface of each slide-piece, means for guiding said slide-pieces and means for connecting said small square plates to the 125 mounting-plate and the slide-pieces from the rear.

3. A keyhole closing or obscuring device, comprising a plurality of small interengaging square plates arranged in a regularly-divided 130 field, a plurality of sliding plates arranged in such manner that one of them cannot be moved until the next has been moved, and upon each of which sliding plates a plurality of said

small square plates are mounted, a spindle passing through each small square plate, a rectangular piece upon the inward end of each spindle, a rectangular space somewhat larger than each rectangular piece in the surface of the back plate around each rectangular piece, a knob attached to the outward end of each spindle in front of the small square plates, and locking devices for the said sliding plates, said locking devices being adapted to be operated by the limited rotation of certain of said knobs.

4. A keyhole closing or obscuring device, comprising a plurality of small interengaging square plates arranged in a regularly-divided field, a plurality of sliding plates arranged in such manner that one of them cannot be moved until the next has been moved, and upon each of which sliding plates a plurality of said small square plates are mounted, a spindle passing through each small square plate, means for allowing a limited rotation in both directions to each of said spindles, a knob on the outer end of each spindle, lever-arms connected to certain of said spindles behind said small plates, bolts adapted to be operated by said certain spindles, and slots in

said sliding plates into which the ends of said bolts are adapted to enter.

5. A keyhole closing or obscuring device, 30 comprising a plurality of small interengaging square plates arranged in a regularly-divided field, a plurality of sliding plates arranged in such manner that one of them cannot be moved until the next has been moved, and upon each 35 of which sliding plates a plurality of said small square plates are mounted, a spindle passing through each small square plate, means for allowing a limited rotation in both directions to each of said spindles, a knob on 40 the outer end of each spindle, means adapted to be operated by a rotation in one direction of certain of said knobs for locking said sliding plates, and means adapted to be operated by a rotation in the reverse direction of cer- 45 tain other of said knobs for locking said sliding pieces.

In testimony whereof I have hereunto set my hand in presence of two subscribing witnesses.
